(57) **CLAIM**

The ornamental design for an audio speaker, as shown and described.

DESCRIPTION

FIG. 1 is a front perspective view of an audio speaker showing our new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a front perspective view thereof, shown with the handle in lifted condition;

FIG. 10 is a back perspective view thereof, shown with the handle in lifted condition; and,

FIG. 11 is a right side view thereof, shown with the handle in lifted condition.

The broken lines in the figures illustrate the portions of the audio speaker and form no part of the claimed design.
